UNITED STATES PATENT OFFICE.

WALTER MAECHLER, OF CHICAGO, ILLINOIS.

ATTACHMENT FOR SEWING-MACHINES.

1,117,206.

Specification of Letters Patent. Patented Nov. 17, 1914.

Application filed November 10, 1913. Serial No. 800,132.

To all whom it may concern:

Be it known that I, WALTER MAECHLER, a citizen of the United States, residing at Chicago, in the county of Cook and State 5 of Illinois, have invented certain new and useful Improvements in Attachments for Sewing-Machines, of which the following is a specification.

This invention relates to button hole and 10 similar attachments for sewing machines, and more particularly to the actuating shaft of such attachments where said shaft is operatively connected to the needle-bar or other reciprocatory part of the machine.

15 It is the object of the present invention to provide an improved connection between the actuating shaft and the needle-bar, whereby an adjustment is rendered possible to adapt the attachment to different makes 20 of sewing machines. This object is attained by means of the structure to be hereinafter described in detail, and in order that the invention may be better understood, reference is had to the accompanying drawing, 25 in which—

Figure 1 is a plan view, showing the application of the invention; Fig. 2 is a cross-section on the line 2—2 of Fig. 1; Fig. 3 is a cross-section on the line 3—3 of Fig. 2, 30 and Fig. 4 is a perspective view of one of the fork branches hereinafter referred to.

Referring specifically to the drawing 5 denotes a button-hole attachment for sewing machines such as is disclosed in the U. S. 35 Patent No. 993070, dated May 23, 1911. The invention is shown in connection with this attachment, but it is not limited thereto, it being applicable with equal facility to other button-hole and similar attachments.

40 At 6 is denoted a rock-shaft which drives the operating elements of the attachment, said shaft deriving motion from the needle-bar 7 of the sewing machine by being coupled thereto.

45 As already stated, the present invention relates solely to the coupling between the rock-shaft and the needle-bar, and a detailed description of the other parts of the attachment is therefore deemed unnecessary.

50 The outer end of the rock-shaft 6 carries a sleeve 8 which is made fast to the rock-shaft and thus forms a part thereof. The rock-shaft is therefore composed of two sec-

tions, and said sections are adjustable so that the rock-shaft may be lengthened or 55 shortened. The sections are locked in adjusted position by a set screw 9 threaded through the sleeve 8 and adapted to be seated in a longitudinal groove 11 in the shaft section 6. It will be noted that there 60 are two or more screw-holes in the sleeve, the ones which are not occupied by the set-screw being indicated at 12. These screw-holes are offset from each other circumferentially of the sleeve, for a purpose to be 65 presently made clear.

To the outer end of the sleeve 8 is fixed an arm 13 shaped at its outer end to form one of the branches 14 of a fork, the other fork branch 15 being adjustably secured to 70 the arm. At the base of the fork-branch 14 the arm 13 has a lateral extension 16 on which is clamped a lateral base portion 17 of the fork-branch 15, the latter being slightly offset to come squarely opposite the 75 fork-branch 14. The part 16 has a slot 18 in which seats a lug 19 on the inner face of the part 17. A screw 20 is threaded into the lug from the outer face of the part 16, the head of the screw engaging the latter, 80 whereby the fork-branch 15 is securely held in place. The slot 18 allows the fork-branch 15 to be adjusted toward and from the fork-branch 14. The contiguous faces of the parts 16 and 17 are serrated as shown, which 85 assists to hold the fork-branch 15 in adjusted position.

The fork-branches 14 and 15 straddle the shank of the needle-holding set-screw 21 carried by the needle-bar 7. It will therefore be seen that the reciprocation of the needle-bar, through the fork arm 13, rocks the shaft 6. The object of the adjustable connection between the shaft 6 and the sleeve 8 is to allow lengthening and shortening so that the fork arm 13 may be placed in proper position relative to the set-screw 21, which latter, in some machines, is located on one side of the needle-bar, and in others on the opposite side. Fig. 1 shows in dotted 100 line how the fork may be set opposite to either side of the needle-bar. The plurality of holes for the set-screw 9 are provided to allow angular adjustment of the sleeve 8 on the shaft 6. This is to adapt the fork 105 arm 13 to rotary and shuttle-needle ma-

chines, the shuttle-needle being longer than the rotary needle; hence the necessity of setting the sleeve to lower the fork arm sufficiently to take the bar of the longer needle.

5 I claim:

In an attachment for sewing-machines, a rock-shaft, a sleeve carried by the rock-shaft, a set screw carried by the sleeve and engageable with the rock-shaft to lock the 10 sleeve and the rock-shaft together, the sleeve having a plurality of holes, any one of

which holes is adapted to receive the set-screw, and said holes being offset circumferentially relative to each other, and means for coupling the sleeve to a reciprocating 15 part of the machine.

In testimony whereof I affix my signature in presence of two witnesses.

WALTER MAECHLER.
